ELECTRONIC SWITCHING SYSTEM

John H. Newitt, Montclair, N. J., assignor to Federal Telephone and Radio Corporation, New York, N. Y., a corporation of Delaware

Application February 23, 1945, Serial No. 579,451

4 Claims. (Cl. 343—121)

1

The present invention relates to electronic switching systems especially adapted for switching ultra-high frequency currents, and particularly to that type of switching in which the current is abruptly switched from completely "off" to completely "on," or vice versa.

In certain applications of switching systems, it is important that the current be abruptly switched, that is, abruptly turned "on" or "off." For example, in several types of direction finders and radio beacons, particularly of the amplitude comparison type, switching systems are employed as goniometers to shift the radiant action patterns of the antenna system. One such direction finding system is illustrated and described in the co-pending application of Nathan Marchand, for "Direction finders," filed November 25, 1944, bearing Serial Number 565,142, now Patent No. 2,448,041 which issued August 31, 1948. For the proper operation of this system, it is important that the energy received be abruptly and completely switched "on" and "off" from one set of antennas to another. When the switched currents are ultra-high frequency, particularly in the range of about 100 to 600 megacycles or over, this becomes quite difficult. Electronic switches which have proved quite satisfactory for lower frequencies become unsatisfactory for the high frequencies, since, if tetrodes are employed, the transit angle becomes so great as to be critical, and if triodes are employed, the energy cannot be completely switched off, even though electronic flow is blocked, due to the interelectrode capacities. Because of these difficulties, the tendency of the art has been towards transmission line or capacitive switching at these ultra-high frequencies despite the superior convenience and other advantages of electronic switching.

An object of the present invention is the provision of an improved electronic switching system which is suitable for abruptly switching completely on and off current of ultra-high frequencies, such as about 100 to 600 megacycles or over.

Another object of the present invention is the provision of an improved shiftable radiant acting system for ultra-high frequency currents utilizing electronic switching of the type herein described.

A still further object of the present invention is the provision of a direction finding system for ultra-high frequency current in which electronic switching of the type described is used to shift the radiant action pattern.

Other and further objects and advantages of the present invention will become apparent and

2

the foregoing will be best understood from the following description of an embodiment thereof, reference being had to the accompanying drawing in which:

5 Fig. 1 is a diagram, partly schematic and partly in block form, of a direction finding system including an electronic switching system embodying my invention;

10 Fig. 2 is a detailed cross-sectional view, partially in elevation, of one of the electronic discharge devices of the electronic switching system showing the ground connection for the grid; and

15 Fig. 3 is a set of curves used to describe the relationship of the switching control voltages of the electronic switching system of Fig. 1.

As shown in Fig. 1, I provide four antenna units 1, 2, 3 and 4, each of which is rendered unidirectional by shield means 5, 6, 7 and 8 respectively. The antenna units illustrated are dipoles and are 20 respectively connected by dual transmission lines 9—12 respectively to known conversion boxes 13—16 respectively. These conversion boxes convert from the balanced dual transmission lines to coaxial lines 17—20 respectively.

25 Coaxial lines 17—20 are sequentially coupled by means of an electronic switching system 21 to a direction finding receiver 22 which has at its output an indicator 23.

Electronic switching system 21 is comprised of 30 four electronic switches 24—27 which are adapted to sequentially couple antennas 1—4 respectively to the direction finding receiver 22. Since all of said switches are similar in construction a description of one of said switches will suffice.

35 Switch 24 includes an electron discharge device or tube 28. Since the electronic switch 24 is adapted to operate over a relatively wide band of frequencies and in the range of about 100—600 megacycles or over—although of course it will be 40 appreciated that this switch may also be used at lower frequencies—a special type of tube in a special arrangement is required.

Tubes satisfactory for use in electronic switch 24 are characterized by the fact that the transit 45 angle is small at the operating frequency, which requires close spacing between the electrodes, and are characterized further by the fact that the anode and its leads are completely shielded from the cathode and its leads by the grid and the grid connector or grid lead. Among types of tubes satisfactory for this purpose are those commercially known as "lighthouse tubes" and various forms of disk seal tubes.

Referring now to Fig. 2, I have there illustrated 50 a known form of lighthouse tube. Tube 28 is a

triode having an anode 29, a grid 30 and a cathode 31 heated by a heater 32. The electrodes 29—31 are provided respectively with low inductance and low impedance leads 33—35. Leads 33 and 34 are in the form of disks. The grid lead or grid disk 34 extends through the walls of the tube envelope 36 along all radii. Grid disk 34 has an opening therein across which the grid 30 extends, said grid and disk both being flat and substantially coplanar and serving as an electrostatic shield shielding the anode and its leads from the cathode and its leads. It will therefore be seen that the grid forms an unbroken continuous shield across the opening of the grid disk 34. Since the grid is flat, the active surfaces of the anode 29 and cathode 31 may be arranged immediately adjacent thereto thereby providing a short transit time.

In accordance with my invention, the grid 30 is maintained at ground potential for radio frequency. I accomplish this by arranging a flat conductor 37 against the upper surface of the grid disk 34, which conductor 37 is separated by a thin insulating member 38, such as a thin sheet of mica, from a conductive surface 39 serving as ground. The surface 39 may be the chassis or frame of the electronic switching system 21 or any similar conductive surface maintained at ground potential. The dimensions of this condenser arrangement 40 should be so chosen that the grid is maintained at ground potential at the operating frequency. Said arrangement provides a non-inductive ground connection which will offer substantially no impedance to radio frequency current and consequently maintain the grid at ground potential. Of course it is to be understood that the conductive member 37 might be omitted and the grid disk 34 serve as one plate of the condenser.

The radio frequency energy from antenna 1, transmitted over coaxial line 17, is impressed upon the cathode 31 of tube 28, the inner conductor 41 of said coaxial line being coupled to the cathode with the outer conductor thereof being coupled to ground. The cathode resistor 42 also serves as the matching terminating impedance of line 17. Through an isolating circuit 43, switching control voltages from a source 44 are transmitted over line 45 to the grid 30 of tube 28 of switch 24. Similarly switching control voltages are supplied from said source 44 and over similar lines 46, 47 and 48 to the grid of the tube in switches 25, 26 and 27 respectively. The anodes of the tubes in said switches are coupled together and to the direction finding receiver 22. They are also connected in series with a tunable resonant circuit in the form of an adjustable resonant line 49 through an isolation network 50 to a source of positive potential B+. Line 49 may be tuned to the frequency at which the system is operating by means of a tuner 51, adjusting the point at which the inner conductor 52 is grounded at radio frequency capacitively. Other forms of tuning may, of course, be employed as well as other forms of resonant sections.

The operation of switches 24—27 is controlled by the conduction of their tubes. Said tubes are adapted to become conductive in sequence and this is controlled by the voltages derived from the source of switching voltages 44. Since the tubes are to be switched abruptly on and off, the source 44 supplies rectangular pulses as illustrated in Fig. 3 to the various lines 45—48 associated with the respective circuits. There

are two general modes of operation. In the first mode of operation, the tubes are normally blocked and the source 44 supplies positive pulses to unblock the tubes sequentially. In a second form of operation, the tubes are normally conductive and the source of switching control voltages supplies blocking voltages to three of the four tubes at a time to block all but one of said tubes, the one of said tubes that is unblocked being changed sequentially. This latter mode of operation will now be described in connection with Fig. 3.

The tubes of the electronic switches 24—27 are normally biased so that said tubes are non-conductive. This biasing voltage may be supplied in series with the source 44 or as a part thereof with the blocking switching control voltages superimposed on the normal bias which latter renders the tubes conductive.

The four curves of Fig. 3 show the switching control voltages applied to the lines 45—48 from source 44. The pulses illustrated in said curves are negative and are adapted to abruptly block the tube to which they are applied. In between said pulses the tubes are conductive. Consequently it will be seen that between time T₀ and T₁ the tube of switch 24, between time T₁ and T₂, the tube of switch 25, between time T₂ and T₃ the tube of switch 26, and between time T₃ and T₄ the tube of switch 27, will alone be conductive. Thus it will be seen that the switches are sequentially operated.

If, however, it is desired to have the tubes normally blocked, the positive pulses are applied for periods from T₀ to T₁ to render switch 24 operative and for like short periods T₁ to T₂ for switch 25, T₂ to T₃ for switch 26, and T₃ to T₄ for switch 27. In this mode of operation only one tube at a time is conductive and the tubes become conductive sequentially.

While I have described my invention in connection with a direction finding system, it is obvious that it may not only be employed with other shiftable radiant acting systems but in many other uses. Furthermore, it is clear that modifications of the electronic switching system disclosed will occur to those skilled in the art. Therefore it should be distinctly understood that this description is given merely by way of illustration and is not to be considered a limitation on my invention as indicated in the objects thereof and defined in the accompanying claims.

I claim:

1. An electronic switch system for switching current from an ultra high radio frequency source to a load comprising an electron discharge device having an envelope, an anode, a cathode, leads for the cathode and anode, a grid, and a low impedance grid lead providing an external terminal for the grid and connected inside the envelope thereto, said grid lead and grid serving as an electrostatic shield between the anode and its lead and the cathode and its lead, means forming a substantially non-inductive capacity coupling said grid lead to ground and of such a value as to maintain said grid at ground potential for the radio frequency current to isolate said anode and said cathode, an impedance means coupling said cathode to ground, means for coupling said source across said impedance means, a source of switching control voltages, means impressing said switching control voltages on said grid, and means coupling the anode to said load.

2. An electronic switching system for switching current from a plurality of ultra high radio

frequency sources to a load including a plurality of electronic switches; each of said switches comprising an electron discharge device having an envelope, an anode, a cathode, leads for the cathode and anode, a grid, and a low impedance grid lead providing an external terminal for the grid and connected inside the envelope thereto, said grid lead and grid serving as an electrostatic shield between the anode and its lead and the cathode and its lead, means forming a substantially non-inductive capacity coupling said grid lead to ground and of such a value as to maintain said grid at ground potential for the ultra high radio frequency current to isolate said anode and said cathode, an impedance means coupling said cathode to ground, means for coupling one of said sources across said impedance means; a source of switching control voltages; means impressing said switching control voltages on the grid of a given number of said switches in a given sequence; and means coupling the anodes of said devices to said load.

3. A shiftable radiant acting system comprising a plurality of differently directed antennas; a translating device; and an electronic switching system for switching current from said antennas to said translating device, said electronic switching system including a plurality of electronic switches each comprising an electron discharge device having an envelope, an anode, a cathode, leads for the cathode and anode, a grid, and a low impedance grid lead providing an external terminal for the grid and connected inside the envelope thereto, said grid lead and grid serving as an electrostatic shield between the anode and its lead and the cathode and its lead, means forming a substantially non-inductive capacity coupling said grid lead to ground and of such a value as to maintain said grid at ground potential for the radio frequency current from said antennas to isolate said anode and said cathode, an impedance means coupling said cathode to ground, means for coupling one of said antennas across said impedance means; a source of switching control voltages; means impressing said switching control voltages on the grids of a given number of said electron discharge devices in a

given sequence; and means coupling the anodes of said electron discharge devices to said translating device.

5. A direction finding system comprising a plurality of differently directed antennas; a direction finding receiver; and an electronic switching system for switching current from said antennas to said receiver including a plurality of electronic switches each comprising an electron discharge device having an envelope, an anode, a cathode, leads for the cathode and anode, a grid, a grid lead providing an external terminal for the grid and connected inside the envelope thereto, said grid lead and grid serving as an electrostatic shield between the anode and its lead and the cathode and its lead, means forming a substantially non-inductive capacity coupling said grid lead to ground and of such a value as to maintain said grid at ground potential for the ultra high radio frequency current to isolate said anode and said cathode, an impedance means coupling said cathode to ground, and means for coupling one of said antennas across said impedance; a source of switching control voltages; means impressing said switching control voltages on the grid of a given number of said electron discharge devices in a given sequence; and means coupling the anodes of said electron discharge devices to said direction finding receiver.
